UNITED STATES PATENT OFFICE.

JOHN M. BUTLER AND HARRY A. TORSON, OF CHICAGO, ILLINOIS, ASSIGNEES TO KING PNEUMATIC TOOL COMPANY.

TOOL RETAINER FOR PNEUMATIC HAMMERS.

Application filed September 10, 1923. Serial No. 661,963.

This invention relates to pneumatic hammers and more particularly to retaining means for holding the working tool, such as a rivet set or chisel, in the forward end or nose of the hammer barrel or cylinder.

Among other objects, the invention is intended to provide improved means for connecting a removable tool with the hammer barrel in such a manner that the tool will be retained reliably against accidental detachment while being readily removable when desired.

The invention will be clearly understood by reference to one illustrative embodiment thereof shown in the accompanying drawings.

In said drawings:

Fig. 1 is a side elevation of a conventional type of pneumatic hammer having means embodying the invention. In this figure a portion of the hammer barrel is shown broken away to reveal interior parts.

Fig. 2 is an enlarged elevation of the forward terminal portion of the hammer, this being the portion equipped with the improved means referred to.

Fig. 3 is a cross section taken on the line 3—3 of Fig. 2, looking in the direction of the arrows and showing parts in end elevation.

Fig. 4 shows the same parts as in Fig. 2 viewed from the bottom.

Fig. 5 shows the same parts as in Fig. 2 viewed from the top.

Fig. 6 is a longitudinal vertical section of the parts shown in Fig. 2.

Fig. 7 is an elevation similar to Fig. 5 but representing the working tool in a position for stretching the connecting means.

Fig. 8 is a side elevation of the parts shown in Fig. 2, representing a manipulation to permit ready detachment of the tool.

Fig. 9 is a top view of the parts, showing the tool released from the retainer.

In the drawings, 1 denotes the cylinder or barrel of a pneumatic hammer.

The pneumatic hammer selected for illustration has an inlet at 4 for admission of compressed air through the handle, while the exhaust air discharges through openings in a so-called exhaust deflector 7. The handle may contain a throttle valve controlled by the lever 6. The cap-like handle base 5, screwed upon the barrel, encloses the

hammer valve head. The hammer piston, 55 reciprocating in the barrel, is shown at 8. All of these parts will be understood by those skilled in the art.

The hammer carries a working tool, represented by a rivet set 2. The shank of the rivet set is shown fitted in the center bore or opening in the nose of the barrel, and receives the impacts delivered by the hammer piston 8. On the head of the rivet set is a flange 10 presenting a shoulder 9 which enters into a function presently to be described.

The tool or rivet set 2, while capable of necessary play or longitudinal movement under the action of the hammer piston, is 70 removably connected with and held in proper operative relation to the barrel by a tool-retaining device indicated at 3 in Fig. 1 and shown more fully in the remaining figures of the drawings.

This device may be considered as comprising three functional parts, namely, an attaching member 12 by which the device is secured to the hammer barrel; a retaining member 15 arranged in front of the flange 10 of the tool and adapted to form a stop or abutment for the shoulder 9 so as to limit the outward movement of the tool; and an intermediate resilient connection 13 by which the retaining member 15 is supported 75 in proper relation to the tool from the attaching means with capacity of being flexed in relation to the barrel.

The attaching member 12 is shown as a stiff contractile ring, which is forced over 90 the nose of the barrel and secured thereto, in this instance, by engagement with an annular groove 20 on the barrel. Advantage may be taken of a taper or bevel 21 on the nose of the barrel for expanding the ring to force 95 it on the barrel and allow it to snap into the groove. Where the nose of the barrel is so tapered or bevelled, the ring may be made of somewhat smaller diameter than otherwise so as to contract tightly in the groove. 100 Thus the retaining device may become practically a permanent attachment to the hammer barrel.

The retaining member 15 is shown as a curved arm extending partially around and 105 hugging the head of the tool, so as to present an abutment in front of the shoulder 9 of the flange 10 of the tool. The terminal

end of said member 15 is bent forwardly as indicated at 19 for a purpose which will presently appear.

The connecting member 13 is shown as an extension from the ring 12, having approximately the form of a spiral, and appropriately curving toward the axis of the hammer so as to hold the retaining member 15 closely around the tool head. (See Fig. 3.)

The retaining device as a whole may be constructed from an integral strip of spring steel, of appropriate form, size and stiffness for the purposes in view. Such a device may advantageously be made from stout spring wire, flattened by rolling. The drawings are intended to illustrate a device so formed.

The flattened wire forming the device may be bent in such a manner that the wider flattened faces of the attaching ring 12 and curved retaining arm 15 are at the sides of these members, or in other words in planes transverse of the axis of the hammer and tool. This increases the transverse stiffness of these parts, while their flattened sides and resulting edges coact effectually with the walls of the groove 20 to resist accidental displacement of the ring 12, and with the tool flange 10 to produce a biting action thereon when force is applied tending to separate the tool from the body. In other words, a flat-sided formation of the attaching ring increases its resistance to displacement from the groove; while a flat-sided formation of the curved retaining arm 15 promotes its capacity to retain the tool, and especially its resistance to disengagement from the tool by camming action of the shoulder 9 or flange 10 against the retaining arm.

In operation, the thrust of the tool flange 10 against the retaining arm 15, under a force tending to separate the tool from the hammer barrel, will tension the retaining device, as represented in Fig. 7 of the drawings. The forced distention and tensioning of the connecting portion 13 of the retaining device will tend to contract the device around its axis; or draw the retaining arm 15 tightly to the tool head, promoting its effectual coaction with the shoulder 9 in the flange 10 of the tool. Thus the harder the force, the harder the retaining device holds the tool, ensuring its effectual retention under all ordinary conditions.

It will be observed that the retaining device is connected to the hammer barrel much more securely than to the rivet set or tool which is removably held in operative position with capacity for longitudinal movement, within the limits allowed by the spacing of the retaining arm 15 from the nose of the barrel. With the specific construction shown, it would obviously require a

much greater force to detach the retaining device from the hammer barrel than to detach the rivet set from the retainer, since the portion of the device attached to the barrel (i. e. the attaching ring 12) extends practically all around and grips the barrel, besides being seated in a narrow groove; while the portion connected to the rivet set (i. e. the retaining arm 15) extends only partially around the tool head, as shown more clearly in Fig. 3; and merely presents an abutment or stop to coact with the tool shoulder 9 for limiting the outward movement of the tool.

Thus the retaining device, after application to the hammer barrel, functions practically as a permanent attachment, while the rivet set or other tool is releasably retained, though effectually enough to prevent dropping out of the rivet set or its accidental detachment by any ordinary force. In fact, for the purposes in view, the retaining device should be, and one constructed as described is ordinarily, stiff enough to resist effectually any effort to pull out the tool by mere manual force, unless such pulling be accompanied by some distortion or adjustment of the retaining device as herein-after explained. Hence the proper retention of the tool under ordinary conditions is ensured, the retaining device being so stiff that its capacity will not be seriously impaired by the vibrations of the hammer or by repeated stressing of the device during removal and insertion of tools.

Assuming the retainer to be attached to the hammer barrel, the rivet set or tool may be attached by inserting the end of its shank in the bore of the barrel, as indicated in Fig. 9, and then driving in the tool by a sharp blow or quick manual thrust, causing the retaining arm to spring and snap past the tool flange 10, so as to lie on the forward side of said flange as shown in Fig. 5. In this action, the compressive stressing of the retaining device tends to expand or move the retaining arm 15 outwardly sufficiently to allow the tool flange 10 to pass it. This outward displacement of the arm 15 may be facilitated by engagement of the flange 10 with the bent terminal or finger 19 before its engagement with the arm. For example, as indicated in Fig. 9, the edge 17 of the flange 10 may ride on the edge 18 of the finger 19, thereby moving the arm 15 outward sufficiently to allow further displacement of said arm and movement of the flange 10 past the retaining arm by a slight blow or quick thrust. The provision of such finger 19 is therefore desirable in cases where the retaining arm 15 may be so stiffly held, or present such an extent of flat surface in opposition to the flange 10, as to oppose seriously the manual insertion of the tool or to require an undesirably severe blow for that purpose.

To remove the tool, the ordinary method would be to eject it by setting the pneumatic hammer into operation while the tool is off the work. When this is done, the intensity 5 of the hammering action on the tool will drive it with such force as to overcome the stiffness of the retainer and allow the tool to shoot out. In the ejection of the tool in this manner, the camming action of the 10 shoulder 9 and flange 10 on the intermediate connection portion 13 of the retaining device will distort the device and allow the flange to drive through. The ejection may be effected without danger of detachment of 15 the tool retainer from the hammer barrel, by virtue of the secure retention of the latter on the barrel, and because, as already indicated, the force required to detach the tool from the retainer is much less than that 20 which would be required to pull the retainer from the barrel.

A capacity for quick ejection of the working tool is desirable, since in the use of 25 pneumatic hammers it may be frequently necessary to substitute one working tool for another. For example, a man operating a 30 pneumatic riveting hammer may have occasion to use, while on the same work, a number of different rivet sets adapted for operation on rivets of different sizes. The rivet set being hot after use, it would be impracticable for that reason, as well as on account of loss of time, to attempt to remove 35 the tool from the retainer by manual manipulation. With a retainer of the illustrative construction, the operator of the hammer may eject a rivet set or other tool at a moment's notice, by shooting it from the hammer, and then quickly insert a substitute 40 rivet set or tool in the retaining device, which remains in its proper position on the barrel.

In other circumstances, it may be necessary to detach the rivet set or tool manually, 45 as for example where the pneumatic hammer is disconnected from the compressed air supply, and happens to have been put away without ejecting the tool, as previously stated, a retainer of the construction described 50 would ordinarily be too stiff to permit removable of the tool by mere manual force, unless the retainer be distorted. In the event of a mere attempt to pull out the tool, the retaining device and especially the intermediate portion 13 will be strained or tensioned, with the effect of inwardly constricting 55 the retaining arm 15, which causes the latter to hug or grip the tool head all the tighter. However, a means for ready manual release of the tool, when necessary, is provided in the illustrative structure.

Such manual release may be accomplished 60 by a slight adjustment or manipulation of the retaining device, indicated in Fig. 8 of 65 the drawings. This adjustment consists in

displacing from the groove 20 the end of the attaching ring 12 contiguous with the connecting portion 13. The portion of the ring referred to may be readily displaced by pressure of the thumbs of the operator while 70 grasping the hammer barrel in his hands. This capacity for displacement is incident to the extension of the connecting member 13 from the attaching ring. A forward pressure on the portion of the connecting member 75 13 adjacent to the barrel will cause said portion to cam on the front wall of the groove 20 and lift the contiguous end portion of the attaching ring 12 out of the groove, as shown in Fig. 8. Such displacement is accompanied by a sufficient displacement of the portion of the retaining device 80 encircling the tool head as to permit the tool to be withdrawn by a sharp pull, in which withdrawal the flange 10 snaps past the retaining arm 15. The rebound of the retaining arm as the tool is drawn out will usually cause the displaced end of the attaching ring to reseat in the groove, under the natural tendency of the device to resume its 85 form.

The rivet set or tool may be otherwise manually detached, for instance by prying the retaining arm 15 away from the head of the tool and over the flange 10, while 90 withdrawing the tool; but this is a more difficult method of detachment than the one just described, and usually necessitates the use of a prying device. Hence in the case 95 of a tool retainer of the advantageous character illustrated in the drawings, the method of manual detachment referred to with reference to Fig. 8, which is easy of accomplishment, is to be preferred to that of prying the retainer to release the tool.

The tool retainer herein described permits adequate longitudinal play of the rivet set or other tool with which it is associated, relieving the retainer of the force and jar of the hammer action, while it yieldably opposes and rebounds from such various stressing as it sustains. It is adapted to withstand prolonged use without serious deterioration of its functional capacities by the jarring or vibration of the hammer, and to 110 withstand rough usage without tendency to become broken or distorted. It is also susceptible of economical manufacture and convenient applicability to the implement on which it is used.

It will be understood that the specific details of construction and arrangement of the illustrative structure may be modified to suit various requirements. Moreover it is not essential that all the features of the invention be used conjointly, since they may be advantageously used in various different combinations and sub-combinations.

Having described an embodiment of our invention, we claim:

1. A tool retainer for pneumatic hammers comprising attaching means for connection with the hammer barrel and a stiff spring arm of approximately spiral curvature extending from said attaching means and having a continuing curved part adapted to closely hug the head of the tool carried by said barrel and to present a stop or abutment in front of a flange on said tool head, said arm adapted to be sprung to permit attachment of the tool by a backward thrust of the tool with resultant compressive stressing of said arm tending to expand or move said stop outwardly to allow the tool flange to pass back of it, and said semicircular stop part having a forwardly projecting terminal finger adapted to be engaged by the back edge of said tool flange before engagement of said flange with said stop part to facilitate the outward displacement of said stop part or initiate its movement sufficiently to allow further displacement to permit backward passing of the tool flange under a backward thrust on the tool.
2. A tool retainer for pneumatic hammers comprising a unitary structure capable of flexing longitudinally of its axis and hav-

ing attaching means for securing it to the hammer barrel and a retaining arm adapted to be sprung laterally to permit attachment or detachment of the tool without disturbing said attaching means, said arm having a forwardly projecting terminal finger adapted to be engaged by a portion of the tool in advance of engagement of the tool with said arm to facilitate attachment of the tool to the hammer.

3. A tool retainer comprising a wire structure having attaching means for connection with a tool supporting body, a tool-retaining arm provided with a forwardly projecting terminal finger and a spirally formed connecting means between said retaining arm and attaching means, said structure being capable of flexing longitudinally of its axis and laterally thereof when said finger is engaged by a tool under stress of inserting the latter in said body and into holding relationship with said tool retaining arm.

In testimony whereof, we have signed our names to this specification.

JOHN M. BUTLER.
HARRY A. TORSON.
